UNITED STATES PATENT OFFICE.

EDWARD S. GILFILLAN, OF BOISE, IDAHO.

AIR-CIRCULATION GARMENT.

1,360,390.

Specification of Letters Patent. Patented Nov. 30, 1920.

Application filed June 19, 1915. Serial No. 34,992.

To all whom it may concern:

Be it known that I, EDWARD S. GILFILLAN, a citizen of the United States, residing at Homefield, R. F. D. No. 1, Boise, in the county of Ada and State of Idaho, have invented a certain new and useful Air-Circulation Garment, of which the following is a specification.

The purpose of my invention is to cool 10 the body of the wearer of one of my garments by air currents up or down, in or out, through the garment, caused by the movement of the body of the wearer and effective because of the construction of the garment.

15 A further purpose of my invention is to form a garment intended for circulation of air upon a pumping principle and preferably to hold the end of the sleeves and legs of the garment away from the wearer in 20 order to increase the effectiveness of the pumping action.

A further purpose of my invention is to support a union garment or separably connected garment intended for air circulation 25 use by suspenders, so that the upper part of the garment may not only be relieved of the weight of the lower part thereof, but spaced from the wearer and fitted for air circulation.

30 A further purpose of my invention is to hold the front and back of the blouse of an air circulating garment away from the body of the wearer and to lift the garment to give shoulder spacing for circulation.

35 A further purpose of my invention is to provide air openings at the side of a garment in connection with spacing means for the upper part of the garment to secure circulation.

40 A further purpose of my invention is to provide air openings for a garment with means for covering them, both to close them and to improve the appearance.

A further purpose of my invention is to 45 provide a suspender-supported union garment with removable closures along the shoulders and outer sides of both arms, as the means of entrance to it.

50 A further purpose of my invention is to removably connect the upper part of a union garment by means of suspenders, preferably at the front and most desirably using the same suspenders by which the lower part of the garment is supported.

Further purposes of my invention will

appear in the specification and particularly 55 in the claims thereof.

I have preferred to illustrate my invention by but one of the various forms in which it may be advantageously used, selecting therefor a form which is simple and inexpensive, which has proved effective in actual use and which at the same time well illustrates the principles of my invention.

Figure 1 represents a man wearing the preferred form of my invention.

Fig. 2 is a vertical section of the garment shown in Fig. 1.

Fig. 3 is a section of the garment of Fig. 1 taken upon a line corresponding to 3—3 of Fig. 2.

Fig. 4 is a broken side elevation of a garment shown in Fig. 1, with the arm raised.

Fig. 5 is a broken elevation of the bottom of one of the legs of the garment in the drawings.

Similar numerals of reference indicate like parts.

The principle upon which my invention operates is that the wearer in working, actually pumps air, that is, forces the air up and down around his body, evaporating any perspiration and cooling him by the air itself and by this evaporation.

I have preferred to form my garment as a union garment, recognizing, however, the 85 fact that the integrality or non-integrality of the upper and lower parts of the garment does not affect the principle of my invention, providing the coöperative structure invented by me be secured. Again, I show the union garment as made up of a blouse (by which term I intend to include all types of covering for the upper part of the body without discrimination between shirts, coat-like structures, garments technically known as blouses and the like) and a nether garment of which I prefer the pantaloons, though the bifurcation of the lower part is not essential. In any event, the combined garment is most useful when worn without other body covering.

In the garment I show arms 10 and legs 11 secured to a body 12. I have formed the parts particularly subjected to greatest wear and strain, including the legs and the front 13 and back 14 of the blouse of a 105 heavier material than is necessary for the remainder of the blouse and the arms, to give weight or "body" or stiffness enough

to these parts so that they will flap with movements of the body to perform the pumping function and to give strength where needed.

5 The blouse is made full at both front and back and with a low neck at 15. In order to give plenty of fullness for the blouse and freedom from strain upon the shoulders, the lower or nether part of the garment is supported by suspenders 16, which may not only lift the nether portion but support part, at least, of the blouse.

If the material of the blouse be sufficiently firm, even actual lifting of the shoulders at 15 17 away from the shoulder of the wearer may be secured at intervals by the suspender support of the nether part of the garment during the movement of the wearer. The fullness of the back and front provide for 20 air pumping action front and back, as the wearer leans forward and subsequently raises his body or arms, which action is rendered more effective by stiffening as at 18 and 19 by which the ends of the sleeves and 25 legs are held away from the wearer and open for air passage. The stiffening may provide enough weight to assist in keeping sleeves and legs from undue wrinkling if desired, though for many uses such weight 30 would prove objectionable.

The air pumping action is also assisted by providing for extension of the sides forwardly and rearwardly by openings or slits in the sides of the garment beneath the arms 35 as at 20. These openings may be of any desired form or length. They are most effective when they extend from the under side of the arm into the nether garment—say half way down the upper leg portion of 40 the pantaloons and are free to flap open and shut with the movements of the wearer to assist in the pumping action. The slits could even be netted as at 21, though reducing their utility. To more effectively 45 avoid exposure of the body through the openings when active work is not being performed, I provide flaps, as at 22, which may be buttoned at 23 to cover the openings, but which are shown as buttoned back from 50 the openings, as at 24.

The garment front is intended to be constructed of relatively firm material, *i. e.* having enough body to tend to fall forward by its own weight. This because of the blouse 55 construction and support would give a pumping action in itself, which is increased by the further movement permitted by reason of the side slitting. The slitting offers the additional advantage of giving 60 increasing air inlet with the additional forward movement of the front. The relatively firm material of the front may, of course, be the same material of which the remainder of the garment is constructed.

65 The garment is provided with removable

fastenings from the neck to the lower end of the sleeve, along the outside of the arm, as at 25, a convenient form, so that it may be opened and entered at the top. Obviously, entrance to the garment may be otherwise arranged. The form shown is, of course, particularly suitable where the blouse is permanently attached to the nether garment.

Where the nether garment is bifurcated 75 and secured to the blouse fixedly, I prefer to provide it with a seat flap 26, buttoned at 27. The suspenders 16 may be removable to facilitate washing and are shown as fastening at the front at 28. In the rear I prefer 80 to attach them removably to the seat flap, as at 29, in order that greater freedom of movement of the body in the garment may be allowed when the flap is opened.

I secure additional support for the blouse 85 portion of the garment to lift it free from the shoulders by fastening the garment, preferably removably, to the suspenders at some such points as 30, finding that I can lift the garment away from the body and shoulders 90 much better by this means with thinner and lighter material, holding it away a much larger part of the time than by dependence upon the support of the lower portion of the garment alone from the suspenders. 95

I prefer to make the points of support in the front rather than at the back and at the front only. In order to prevent the garment from clinging too closely to the front of the wearer, I provide spacers in the form 100 of pads upon the under side of the garment, as at 31, placing them near enough to the fastenings 30, so that the fastenings shall not pull the garment in toward the wearer objectionably and shall not interfere with 105 the pumping action which I aim to secure. The character of fastenings at 30 should also be accommodated to this function.

In operation, the bending of the body of the wearer forward and backward, as well 110 as the lowering and lifting of the arms of the wearer cause the spaces at the back and front, respectively, between the blouse and the body of the wearer the one to be reduced and the other increased alternately with co-incident rush of air from the one space and into the other. Substantially the entire front and back of the garment at the middle swing away from and toward each other, respectively, opening and closing the side 115 vents. A part of the air pumped by the alternate closing of these spaces at the upper back and front passes from the one space about the sides of the wearer and into the other space; and practically all of the air admitted 120 as the wearer leans forward and expelled as he straightens or leans backward, *i. e.*, pumped by the opening and closing of the middle part of the garment, is driven out of the garment through one or more of the 125 130

openings at the neck, sleeve ends, open sides and at the bottoms of the legs. The result is a nearly continuous circulation of pumped air between the wearer and the garment, 5 which in practice has been found to pass up and down the legs as well as in and out the sleeves, evaporating the perspiration and giving a three fold benefit. It avoids the objection of the presence of the perspiration itself, the air cools by its own circulation, and the evaporation of the perspiration causes heat units to be absorbed in the operation.

In my consideration of the slitted sides of 15 the garment, I have regarded these sides as open when the slitting was capable of opening and closing effectively to accommodate the pumping action, even where the space left open by the slit is somewhat covered by 20 netting or other quite porous means of obscuring the view of the body of the wearer.

It will be evident that various parts of my invention are not only separately new but highly advantageous in separate use as well 25 as in combination with other features making up my preferred form shown.

It will be evident that the support for the parts away from the body, as well as the inlet and outlet air spaces, and the spacing 30 from the body, so as to secure spacing and pumping action, may be obtained by other means than have been illustrated by me, without departing from the spirit and scope of my invention and that the detail even of 35 the particular means shown by me may also be greatly varied.

Having thus described my invention, what I claim as new and desire to secure by Letters Patent is:—

40 1. An air-pumping union garment having a blouse full in the front and back and provided with air inlet within the body of the garment, in combination with sides weakened relatively to the front and back of the 45 garment to yield circumferentially by reason of the weight of the garment to allow the front to fall away with respect to the back, as the wearer leans forward and to facilitate approach of the front toward the 50 back of the garment as the wearer rises to erect position, whereby the air content of the garment is changed by reason of change in the inclination of the body of the wearer and air is pumped through the garment by 55 the movement of the upper part of the garment to and from said body.

2. An air-pumping union garment having a blouse full in the front and back, spaced from the wearer at the back and upper front 60 and provided with air inlet within the body of the garment, in combination with sides weakened relatively to the front and back of the garment to yield circumferentially to allow additional movement of the front with 65 respect to the back, as the wearer leans for-

ward and to facilitate approach of the front toward the back of the garment as the wearer rises to erect position, whereby the air content of the garment is changed with movements of the wearer and air is pumped 70 through the garment.

3. A union garment having the sides slitted from a point in the blouse down into the nether part of the garment and adapted to be worn with this slitted portion open 75 and having a relatively firm front adapted to fall away from the body as the wearer leans forward, by reason of the play given by the slitting and to be pulled toward the wearer to force air out from the space between, as he raises his body.

4. A union garment having a full breast and back in the upper portion and slitted at the sides from a point in the blouse beneath the arms down into the nether part 85 of the garment and adapted to be worn with the slit open.

5. A union garment having the sides slitted from a point in the blouse down into the nether part of the garment and adapted 90 to be worn with this slitted part open and a front adapted to fall away from the body as the wearer leans forward and to be pulled toward him as he raises his body, in combination with a support for the blouse taking the weight of a portion of the blouse 95 away from the shoulders of the blouse.

6. A union garment comprising a blouse full at the front and back and provided with shoulders and a nether garment having the 100 sides adapted to admit air and capable of extension forwardly during the normal wearing of the garment relatively to the front from a point in the blouse above the waist to a point below the waist in the 105 nether part of the garment and a front adapted to fall away from the body, admitting air as the wearer leans forward, and to be pulled up toward the wearer to force the air out as he raises his body, in 110 combination with suspender support for the nether part of the garment at about the waist line, giving play to the fullness of the blouse.

7. A union garment whose blouse is provided with a full front and back having sides adapted to admit air from a point in the blouse to a point down in the nether part of the garment and a front adapted to fall away from the body between these 115 points during the normal wearing of the garment as the wearer leans forward, drawing the air in, and to be pulled up toward the wearer to force the air out as he raises his body, in combination with a spacer holding the blouse away from the wearer at its upper front portion.

8. A union garment comprising a blouse full over the shoulders and a nether garment, and suspenders attached to the upper 120 125 130

- part of the blouse in proximity to the shoulders tending to lift the shoulders of the blouse from the shoulders of the wearer, the suspenders being attached also to the upper 5 part of the nether garment.
9. A union garment comprising a low-necked blouse full over the shoulders and having openings beneath the arms and a nether garment, a spacer holding the upper 10 part of the blouse away from the wearer, a support for the upper part of the blouse from the shoulders of the wearer, taking its weight from his shoulders, and a support for the nether garment separate from its 15 connection with the blouse, and taking its weight from the blouse to give play to the front and back of the blouse.
10. A union garment having a full breast and back and provision for air inlet at the 20 sides, the main fabric being adapted to be separated for a distance at the sides below the arm pits, in combination with a more pliable material than the main fabric joining the separated edges.
11. A union garment having the sides adapted to admit air and capable of extension forwardly relatively to the front from a point in the blouse above the waist to a point below the waist in the nether part of 25 the garment and a front adapted to fall away from the body, admitting air as the wearer leans forward, and to be pulled up toward the wearer to force the air out as he raises his body, in combination with suspender support for the nether part of the 30 garment at about the waist line giving play to the fullness in the blouse.
12. A union garment comprising a low-necked blouse full over the shoulders and 40 having openings beneath the arms and a nether garment, a spacer holding the upper part of the blouse away from the wearer, a support for the upper part of the blouse from the shoulders of the wearer, taking its weight from his shoulders, and a support 45 for the nether garment separate from its connection with the blouse, and taking its weight from the blouse to give play to the front and back of the blouse.
13. In a garment, a low-necked blouse 50 full at the front and back and stiffer at these parts than at the sides, in combination with short full sleeves allowing free air passage therethrough.
14. A union garment comprising a low-necked blouse, full over the shoulders and at 55 the front and back, sleeves and legs for the garment and stiffeners separate from the fabric for holding the ends of the sleeves 60 open.
15. A union garment comprising a blouse full at the front and back, and a nether garment, united thereto to permit air passage from one to the other, sleeves and legs for the garment and stiffeners separate from the fabric for holding the ends of the legs open. 65
16. A union garment, full at the front, having the sides open for air admission and extensible forwardly, permitting the front to fall away from the body as the wearer leans forward and to be pulled toward him as he raises his body, in combination with sleeves therein and stiffening ribs at their outer ends to hold them away from the arms. 70
17. A union garment, full at the front, having the sides open for air admission and extensible forwardly, permitting the front to fall away from the body as the wearer leans forward and to be pulled toward him as he raises his body, in combination with stiffener ribs for the bottoms of the legs to hold them away from the wearer. 75
18. A union garment comprising a low-necked blouse, full over the shoulders and there supported free from the wearer, sleeves and legs for the garment and stiffeners for the ends of the sleeves and legs, separate from the garment fabric and holding the ends extended. 80
19. A blouse, a nether garment secured thereto, stiffeners separate from the fabric for holding the sleeves of the blouse open, suspenders for the nether garment, and a connection between the upper part of the 85 suspenders and the blouse taking the weight thereof from the shoulders of the blouse and tending to lift the blouse from the shoulders of the wearer. 90
20. A low necked blouse, full at the front and back, provided with air openings and adapted to fall away from and be drawn toward the wearer with movements of the wearer, stiffeners separate from the fabric for holding the ends of the sleeves open and a spacer holding the upper part of the front of the blouse away from the wearer. 100
21. A low cut blouse, full in the front and back and over the shoulders and provided with air openings in the sides and there capable of extension, adapting the front to fall away from and be drawn toward the wearer with movements of the wearer and a support for the upper part of the blouse near the shoulders from the shoulders of the 105 wearer taking the weight of the lower part of the blouse from the shoulders of the blouse. 110
- 115

EDWARD S. GILFILLAN.
